CLAIM

The ornamental design for a bottle opener, as shown, and described.

DESCRIPTION

FIG. 1 is a perspective view of the bottle opener;
 FIG. 2 is a front view thereof;
 FIG. 3 is a rear view thereof;
 FIG. 4 is a side view thereof;
 FIG. 5 is a top view thereof; and,
 FIG. 6 is a bottom view thereof.
 The broken lines represent unclaimed matter and form no part of the claimed design.
